Inventor
Oscar Maurer
By his Attorney
Philip S. McLean.

UNITED STATES PATENT OFFICE.

OSCAR MAUNER, OF RICHMOND HILL, NEW YORK.

SUNSHADE.

1,351,839.

Specification of Letters Patent Patented Aug. 31, 1920.

Application filed April 1, 1920. Serial No. 270,550.

To all whom it may concern:

Be it known that I, OSCAR MAUNER, a citizen of the United States, and a resident of Richmond Hill, Queens county, and State of

5 New York, have invented certain new and useful Improvements in Sunshades, of which the following is a specification.

The objects of this invention are to provide a sunshade for the windshields of 10 vehicles which will be relatively light and inexpensive and easily attached to the cars now in use, and which will effectually protect the motorist from the glare and heat of the sun.

15 Special objects are to provide a device of this character which will be capable of the adjustment necessary to enable its use with different types and styles of vehicles and which, in addition to serving the useful purposes outlined, will be attractive and ornamental in appearance.

In the accomplishment of these and other objects, I have developed a number of novel features of construction, combinations and 20 arrangements of parts, as will be set forth in the course of the following specification.

In the drawing accompanying and forming a part of this specification, I have illustrated the invention embodied in one of its 25 simplest and most practical forms, but wish it understood that the structure may be modified without departure from the true spirit and scope of the invention as herein defined and claimed.

25 Figures 1 and 2, in the drawing referred to, are broken front and side elevations, illustrating the invention applied to a typical windshield construction.

Fig. 3 is a broken plan and partly sectional view of the same.

Fig. 4 is a detached enlarged view of one of the angular supporting brackets.

Fig. 5 is a sectional view of the truss supporting bracket as taken on substantially 45 the plane of line 5—5 of Fig. 2.

Fig. 6 is a plan view illustrating a method of making up the covering and engaging the supporting frame therein.

The windshield shown is of more or less 50 conventional form, embodying upper and lower panels 7 and 8 pivotally supported at 9 and 10 between standards 11. The upper panel is usually held in adjusted relation by clamp screws operating on the supporting 55 pivots or journals of the panel. These screws are indicated in the form of wing

nuts 12 and in the illustration are shown as engaged with the projecting screw-threaded stems 13 of the journals of the panel.

The sunshade is made up, in the present disclosure, of a suitable fabric, such as awning material 14, stretched over a frame, consisting of a substantially U-shaped frame element 15, whose ends are connected by an interposed tubular spacing element 16.

The panel thus formed, is supported by brackets having spindles 17, entered through eyes 18, in the ends of the U-frame into the ends of the tube and provided with angularly offset base portions 19, engageable beneath the clamping screws of the upper windshield panel. In the illustration, these base portions are perforated, at 20, to fit over the screw extensions 18 and these perforations are open at the underside of the 75 brackets, at 21, to enable their being hooked over the screws without having to first remove the wing nuts.

The telescopic engagement between the tubular portion of the panel and the supporting brackets enables relative adjustment of these parts to fit windshields of different widths. By providing a return curve or "gooseneck" 22, in the angularly projecting portion of one or both brackets, the base 80 portions of the brackets can be brought closer together, to fit narrow windshields and at the same time the brackets may be set as far apart as necessary, to fit wider windshields. This construction enables me to 85 make the parts all of one standard size, to fit the different size windshields now in use.

Suitable means are provided for supporting the shade at the desired angle, such means taking the form, in the present disclosure, of the struts or trusses 23, pivoted to the studs 24, projecting from the sides of the frame and adjustably held by clamp screws 25, in passages provided in the brackets 26, which are secured by clip bolts 27, at 100 the proper height on the windshield standards. The projecting pivot studs 24, may be welded or riveted to the sides of the frame, or may be engaged with the frame as by screwing them in place, after the fabric has 105 been stretched over the frame.

The awning material may be secured to the frame in different ways, but a practical and preferred method is the one illustrated in Fig. 6, wherein a single piece of fabric 110 is employed, folded or doubled over at the edge 28, and stitched at 29, around the other

three edges, into the form of a bag, which is closed except for the openings 30, left in the corners, at one edge, to expose the eyes in the ends of the U-frame. The frame is 5 engaged in the bag, by entering one end thereof through the opening in one corner, as indicated, and then relatively turning the frame and bag, as shown in dotted lines, to bring the long bar of the frame to the 10 front and finally to seat the frame within the bag, with only the eyes at the ends thereof exposed at the open corners. The spacing tube may then be inserted and engaged between the ends of the frame, after 15 which the spindles of the brackets may be inserted in the sockets thus provided therefor, as shown in Fig. 3.

To hold the awning frame in laterally adjusted position on the supporting brackets, I may use spacing devices, such as the 20 collars 31, shown in Fig. 3, as adjustably secured on the bracket spindles by set screws 32, at the ends of the frame and forming stops limiting sidewise movement of the 25 frame.

In applying the invention to the windshield, it is simply necessary to loosen the clamp screws for the upper windshield panel sufficiently to enable the supporting 30 brackets being engaged beneath the same. The brackets are then turned on their centers of support, either upwardly or downwardly, to bring the upper edge of the awning to the desired level. Usually this 35 upper edge will be brought up into engagement with the overhanging portion of the "stop," as indicated in the full lines in Fig. 2, but the brackets may be swung about their pivots to place the awning at different 40 heights, as indicated by the dotted lines. This capability of adjustment, together with the angular adjustment afforded by the supporting struts, enables the shade to be placed at any time where it will afford the 45 best protection. This makes it possible to avoid the glare usually experienced when driving toward the sun and also makes it possible to eliminate many of the windshield reflections, so objectionable in night 50 driving. The shade afforded from the heat of the sun is also a great advantage and the invention will be seen to possess many other advantages, not necessary here to mention.

While I have illustrated herein only one 55 of the practical embodiments of the invention, I wish it understood that the invention may be embodied in other forms without departing from the true spirit and scope of the invention as will be clear from the scope 60 of the appended claims.

What I claim is:

1. The combination with windshield standards and a windshield panel pivotally hung therebetween and provided with clamps at 65 the pivotal supports thereof for securing

the same in different angularly adjusted relations, of a sunshade panel overstanding said windshield panel and provided with bearings at the opposite ends of the same, adjustable supporting brackets for the sun 70 shade having base portions pivotally engaged with and detachably held by the windshield panel clamps and having offset oppositely disposed bearing elements at the opposite sides of the windshield pivotally 75 engaged with the bearings at the ends of the sunshade panel, and means for securing the sunshade panel in various angularly adjusted relations over the windshield panel.

2. A sunshade for attachment to automobile windshields comprising a substantially U-shaped frame, a tubular element bridging the open side of said frame, supporting brackets having spindles projecting through the sides of said frame and adjustably engaging in the ends of the tubular element, said brackets having angularly projecting base portions perforated to receive supporting means, and a covering over the frame thus formed, said frame being held together 80 by the spindles of the supporting brackets.

3. The combination with the standards of a windshield, a panel pivoted on said standards and clamp nuts for securing the panel in angularly adjusted relations, of brackets 95 having base portions pivotally engaged beneath and adjustably held by said clamping nuts and angularly extending spindles offset forwardly from such base portions and projecting inwardly toward each other at 100 opposite sides of the windshield, a tube telescopically engaged at its opposite ends with said spindles, a forwardly projecting substantially U-shaped frame having perforated ends supported by the spindles at opposite 105 ends of the tube, sunshading material carried by the frame thus formed and means for supporting the frame in different angularly adjusted relations.

4. The combination with the standards of a windshield, a panel pivoted on said standards and clamp nuts for securing the panel in angularly adjusted relations, of brackets having base portions pivotally engaged beneath and adjustably held by said clamping 115 nuts and angularly extending spindles offset forwardly from such base portions and projecting inwardly toward each other at opposite sides of the windshield, a tube telescopically engaged at its opposite ends with 120 said spindles, a forwardly projecting substantially U-shaped frame having perforated ends supported by the spindles at opposite ends of the tube, sunshading material carried by the frame thus formed, means for 125 supporting the frame in different angularly adjusted relations and co-operating stops for relatively positioning the frame on the supporting spindles.

5. The combination with the standards of 130

a windshield, a panel pivoted on said standards and clamp nuts for securing the panel in angularly adjusted relations, of brackets having base portions pivotally engaged beneath and adjustably held by said clamping nuts and angularly extending spindles offset forwardly from such base portions and projecting inwardly toward each other at opposite sides of the windshield, a tube telescopically engaged at its opposite ends with said spindles, a forwardly projecting substantially U-shaped frame having perforated ends supported by the spindles at opposite ends of the tube, sunshading material carried by the frame thus formed, means for supporting the frame in different angularly adjusted relations, including struts extending between the frame and the windshield standards, brackets adapted to support said struts and U-bolts clipped about the standards and securing said brackets thereto. 20

6. A windshield sunshade comprising a bag closed except for two corners at one edge thereof, a substantially U-shaped frame engaged in said bag and having its ends exposed at the openings in the corners of the bag and supporting brackets having supporting base portions and carrying spindles engaged with said thus exposed ends of the frame and a tubular member within the bag 25 extending between the ends of said frame and forming at its opposite ends sockets with which the spindles engage. 30

In witness whereof, I have hereunto set my hand this 30th day of March, 1920.

OSCAR MAURER.
